UNITED STATES PATENT OFFICE.

MORSE STEWART, OF DETROIT, MICHIGAN.

GASIFIER.

No. 853,653.

Specification of Letters Patent.

Patented May 14, 1907.

Application filed February 27, 1907. Serial No. 359,632.

To all whom it may concern:

Be it known that I, MORSE STEWART, a citizen of the United States, residing at Detroit, county of Wayne, State of Michigan, have invented a certain new and useful Improvement in Gasifiers; and I declare the following to be a full, clear, and exact description of the same, such as will enable others skilled in the art to which it pertains to make and use the same, reference being had to the accompanying drawings, which form a part of this specification.

My invention relates to an improvement in gasifiers, an apparatus for producing a fixed or superheated gas from liquid hydro-carbons, shown in the accompanying drawings, and more particularly set forth in the following specification and claims.

In the drawings: Figure 1 is a cross-sectional view through my invention showing parts in elevation. Fig. 2 is a horizontal sectional view through the same showing parts in plan. Fig. 3 is an elevation of a gas engine showing the connections between the same and the gasifier,—the ordinary carbureter, the gasoline pump and the connection between it and the source of gasoline supply.

The object of my invention is to put upon the market an apparatus that will convert gasoline into what may be regarded as a fixed or dry gas. I accomplish this result by conducting the gasoline through coils in a chamber containing the hot gases from the exhaust of the engine. The gasoline after traversing the coil and being subjected to the heat of the exhaust is afterward released in an inner chamber;—at this point the exhaust gases from the engine are also introduced, which, commingling with the spheroidal particles of the released gasoline, completely gasifies the gasoline spheroids and at the same time superheats the gas.

Referring to the letters of reference shown on the drawings, A is the gasifier; B is a gas engine; C is a gasoline pump operated by said engine; C' is a pipe to conduct the gasoline from the source of supply to the pump; C² is a pipe leading from the pump to the gasifier.

D is a carbureter of any suitable type, D' is a pipe to conduct the gas from the inner chamber of the gasifier to the carbureter and D² is a pipe leading from the carbureter to the combustion-chamber of the engine.

E is a pipe to conduct the exhaust from

the engine to the gasifier and E' is an exhaust pipe leading from the gasifier to the muffler or atmosphere.

Referring now more particularly to the construction of the gasifier, it will be seen by reference to Figs. 1 and 2, that it consists of an outer jacket A' inclosing the inner chamber F suitably supported within the same. Surrounding the inner chamber is a coil C³ connected with the pipe C² leading from the gasoline pump, the end of the coil C³ terminating in a valve casing G supported in the walls of the inner chamber F. The casing G forms a seat for two valves, viz., the needle valve g, controlling the admission of gasoline to the interior of the inner chamber, and the valve G', closing the ports G² through which pass exhaust gases from the engine to the inner chamber. The needle valve g is provided with a deflector g' designed to encounter the incoming gasoline to project it downwardly and over the incoming exhaust gases admitted through the ports G².

g² is the stem of the needle valve g suitably guided in a bracket arm G³ attached to the wall of the inner chamber.

g³ is a spider frame formed in the upper portion of the valve G' and resting on the deflector g' of the needle valve g, the construction providing means whereby on opening or closing the needle valve g the valve G' will be likewise operated.

H and H' are diaphragms secured in the upper and lower faces of the inner chamber respectively.

I and I' are stems projecting into the inner chamber from the center of the diaphragms, the stems I' being preferably screw threaded to engage a sleeve I² also inclosing the upwardly projecting end of the stem I. The sleeve may be fixedly secured to the stem I' by a set screw i.

I³ is a projecting lug on the sleeve I² to provide a bearing i' for the forked lever J designed to operate the valve g, the forked portion of the lever straddling a pin g⁴ on the valve stem g².

K is a collar secured to the stem I having a projecting lug in which is pivoted the lever J.

The operation of this invention will be readily understood. Gasoline is pumped from the source of supply through the coils C³ in the gasifier under suitable pressure to the valve g controlling its admission to the inner chamber. While circulating through

the coils, it is subjected to the action of the heat of the exhaust gases delivered from the engine through the pipe E. The temperature of the gasoline is thus materially raised and the pressure of the exhaust gases bearing on the diaphragms H and H' serves to depress them, thereby operating the inwardly projecting stems I, I', and the sleeve I² connected with the rocking lever J. The construction and arrangement of these parts provide for an extended movement of the lever J, which raises the valves g and G', admitting the exhaust gases and gasoline to the inner chamber, the latter entering in a spheroidal condition is deflected downwardly in the form of an encircling apron surrounding the incoming exhaust gases. This action results in a commingling of the two, by which a complete vaporization is obtained, producing what may be regarded as a fixed or superheated gas. The balance of the exhaust from the engine, as will be readily understood, passes out through the pipe E to the muffler or atmosphere. The superheated gas from the inner chamber passes out through the pipe D' to the carburetor or mixer D, where an explosive mixture is formed which passes to the engine. On the cutting off of the exhaust from the engine, the pressure in the outer chamber drops below that of the inner chamber. This results in distending the diaphragms due to the pressure of the gas in the inner chamber, thereby forcing the valves to their seats.

Having thus described my invention, what I claim is:

1. In an apparatus of the character described, a chamber to receive the exhaust gases from an engine, a coil housed within said chamber to receive and conduct liquid hydro-carbon, an auxiliary chamber communicating with the coil and also with the chamber receiving the exhaust gases from the engine, and suitable valves for controlling the admission of the exhaust gases and the liquid hydro-carbon to said auxiliary chamber, substantially as described.
2. In an apparatus of the character described, a chamber to receive the exhaust gases from an engine, a coil housed within said chamber to receive and conduct liquid gasoline, an auxiliary chamber communicating with the coil and also with the chamber receiving the exhaust gases from the engine, valves for controlling the admission of the exhaust gases and gasoline to said auxiliary chamber, suitable piping connecting said auxiliary chamber with a mixer or carburetor, and the carburetor, substantially as described.
3. In an apparatus of the character described, a chamber to receive the exhaust gases from an engine, a coil housed within said chamber adapted to receive a liquid hydro-carbon, an auxiliary chamber commu-

nicating with said first named chamber and also with the coils for conveying the liquid hydro-carbon, valves to control the admission of the exhaust gases and the liquid hydro-carbon to said chamber, and means for operating the valves, whereby the liquid hydro-carbon may be admitted to said auxiliary chamber and also the exhaust gases for gasifying said liquid hydro-carbon, substantially as described.

4. In an apparatus of the character described, a chamber designed to receive the exhaust gases from an engine, a coil housed within said chamber, means for conducting liquid hydro-carbon to said coil from a suitable source of supply, an auxiliary receptacle housed within the first named chamber communicating with the outside chamber and with the coil, said means of communication being under the control of suitable valves, the valves, and means for operating said valves to admit the exhaust gases and the liquid hydro-carbon to the auxiliary receptacle, whereby the liquid hydro-carbon and exhaust gases may commingle for producing a superheated gas, substantially as described.

5. In an apparatus of the character described, a chamber adapted to receive the exhaust gases from an engine, a coil housed within said chamber designed to receive and conduct a liquid hydro-carbon, an auxiliary receptacle housed within the chamber, valves controlling the admission of the liquid hydro-carbon and the exhaust gases to said auxiliary receptacle, said latter receptacle provided with diaphragms, means connected with said diaphragms for operating said valves when the diaphragms are depressed, the construction being such that pressure exerted on the outside of said diaphragms will open the valves admitting the liquid hydro-carbon and exhaust gases to the inner receptacle, substantially as described.

6. In an apparatus of the class described, an outer and an inner receptacle, a coil to conduct a liquid hydro-carbon housed between the outer and inner receptacle, means for conducting the exhaust gases from an engine to the outer receptacle, means for delivering the liquid hydro-carbon to the coil under pressure, valves controlling the admission of the liquid hydro-carbon and the exhaust gases to the inner receptacle, means for deflecting the liquid hydro-carbon as it is projected into the inner chamber over the incoming exhaust gases, and means for opening the valves operated by the pressure of the exhaust gases in the outer receptacle, substantially as described.

7. In an apparatus of the character described, an outer chamber, an inner chamber, diaphragms forming a portion of the wall of the inner chamber, a coil to conduct liquid hydro-carbon from a source of supply located between the inner and outer chambers, valves

to control the admission of the exhaust gases from the outer to the inner chamber and the liquid hydro-carbon from the coil, means for spraying and deflecting the incoming hydro-carbon over the incoming exhaust gases, and means connected with the diaphragms of the inner chamber for operating said valves, substantially as described.

8. In an apparatus of the character described, a chamber to receive the exhaust gases from an engine, a coil housed within said chamber to receive and conduct gasolene to an auxiliary chamber, the auxiliary chamber also having communication with the main chamber, a valve to control the admission of the exhaust gases from the main chamber to the auxiliary chamber, a valve to control the admission of gasolene from the coil to the auxiliary chamber, the construction being such that on raising the valve con-

trolling the admission of gasolene the valve admitting the exhaust gases to the auxiliary chamber will also be lifted, diaphragms forming a portion of the wall of the auxiliary chamber, inwardly projecting stems secured to said diaphragms arranged in alinement, a sleeve secured to one of said stems and free to travel over the opposite stem, and a valve-operating lever fulcrumed to one of the stems and pivoted to the sleeve engaging the stem of the valve controlling the admission of gasolene to the auxiliary chamber, substantially as described.

In testimony whereof, I sign this specification in the presence of two witnesses.

MORSE STEWART.
